CONTAINER FOR HOLDING AND DISPENSING PACKAGED CIGARETTES

Jules Tant and Angeline Tant, St. Charles, Ill.

Application May 2, 1949, Serial No. 2,375

Term of patent 7 years

(Cl. D52—2)

To all whom it may concern:

Be it known that we, Angeline Tant and Jules Tant, both citizens of the United States and residents of the city of St. Charles, in the county of Kane, and State of Illinois, have invented a new, original, and ornamental Design for a Container for Holding and Dispensing Packaged Cigarettes, of which the following is a specification, reference being had to the accompanying drawing, forming part thereof.

Figure 1 is a front view of a container for holding and dispensing packaged cigarettes, showing our new design;

Figure 2 is a top plan view of the container shown in Figure 1;

Figure 3 is a side view thereof as seen from the right side and which is the same as the opposite side;

Figure 4 is a rear view of the container; and, Figure 5 is a bottom view thereof.

The characteristic features of our design reside in the portion shown in full lines.

We claim:

The ornamental design for a container for holding and dispensing packaged cigarettes, as shown, and described.
